SOFA BED COMBINATION

John P. Cleese, Jr., San Francisco, Calif.

Application January 11, 1954, Serial No. 28,476

Term of patent 7 years

(Cl. D15—11)

Fig. 1 is a top plan view of a sofa bed combination showing my new design.

Figs. 2 and 3 are front and end elevational views, respectively, thereof.

Fig. 4 is a front perspective view, on a reduced scale, of the sofa bed combination.

Fig. 5 is a front perspective view thereof, on a reduced scale, illustrating the article in position for use as a bed.

The end of the sofa bed combination not disclosed in the drawing is the same in appearance as the end shown in Fig. 3.

I claim:

The ornamental design for a sofa bed combination, as shown and described.
